UNITED STATES PATENT OFFICE.

FRANK M. CLARK, OF ST. AUGUSTINE, FLORIDA, ASSIGNOR OF ONE-THIRD TO EDWARD M. L'ENGLE, OF JACKSONVILLE, FLORIDA.

COMPOUND RAIL.

1,181,064.

Specification of Letters Patent. Patented Apr. 25, 1916.

Application filed July 14, 1915. Serial No. 39,901.

To all whom it may concern:

Be it known that I, FRANK M. CLARK, a citizen of the United States, residing at St. Augustine, in the county of St. John and 5 State of Florida, have invented certain new and useful Improvements in Compound Rails; and I do hereby declare the following to be a full, clear, and exact description of the invention, such as will enable others 10 skilled in the art to which it appertains to make and use the same.

My invention relates to improvements in compound rails, and it consists in providing an all-metal compound rail, the parts of 15 which may be readily assembled and disassembled, as will be hereinafter described; and in which simplicity of construction is combined with great strength and rugged efficiency to withstand the usage to which 20 such rails are ordinarily subjected.

My invention is especially intended to provide a rail adapted to support heavy weights, and not so liable to fracture as are the rails made of a single piece which are 25 now generally in use.

Reference is had to the accompanying drawings, in which similar reference symbols indicate similar parts throughout the several views.

30 Figure 1 is a perspective view showing one of the pair of rails mounted on a road-bed; Fig. 2 is a perspective view showing the mode of assembling the parts of the rail; and Fig. 3 is a perspective view showing 35 how the rail is jointed.

A represents a bed-plate or stringer having laterally-extending flanges a and overhanging ribs a' , forming with the flat inner bottom a^0 of the stringer a groove adapted 40 to receive the feet of the rail segments B. These rail segments B are made symmetrical each corresponding to one half of the main body of the rail, and when mounted in place form the usual head b of the rail, and the 45 usual shaped web; while the toe of the foot b' of the rail segments engages beneath the corresponding overhanging rib a' , and the heel of said foot is rounded, as at b^2 , the sole of the foot being flat, as at b^1 .

50 In assembling the parts, the stringer A is first secured on the cross ties C in the usual

way, and spiked in place by the spikes D, then one side of the rail is put in place and afterward the adjoining rail segment is put in place from the opposite side, as shown in 55 Fig. 2; the toe b' being caused to engage beneath the rib a' , and the rounded heel b^2 of the segment will permit the second segment to be swung to the position shown in Figs. 1 and 3, when the parts are secured together 60 in the usual way, as by the bolts E. The bolts E pass through the bolt holes b^0 , which are preferably elliptical in shape so as to allow of the expansion and contraction of the rail segments.

When the parts are secured together we have a compound rail formed of a base plate and two abutting members rigidly secured together. By this construction the built-up rail may be made of the three members referred to, and can be constructed very much more cheaply than an integral rail of the same strength and similar dimensions. In addition to the bolts E, suitable fish-plates 70 may be supplied to reinforce the joints if 75 desired, but in practice such fish-plates would ordinarily be unnecessary.

It will be obvious that the shape of the head of the rail may be varied to suit varying traffic conditions, and that various other 80 changes might be made in the construction, combination and arrangement of parts which could be used without departing from the spirit of my invention.

Having thus described my invention what 85 I claim and desire to secure by Letters Patent of the United States is:—

1. A compound rail comprising a channeled bed-plate or stringer having overhanging ribs, and a pair of rail segments 90 each having a web and a head, and having flat inner sides adapted to abut against each other, and each provided with a foot having a toe adapted to engage beneath one of said over-hanging ribs, and with a rounded heel, 95 substantially as and for the purposes described.

2. A compound rail comprising a bed-plate or stringer having a groove therein, the said groove having a flat bottom and undercut sides, and two symmetrically disposed rail segments each having a web and a head, 100

and a flat inner surface adapted to abut against the corresponding rail segment, and each provided with a foot having a flat bottom adapted to rest on the bottom of said groove, a toe adapted to engage in the undercut portion of said groove at one side thereof, and each also provided with a

rounded heel whereby the rail segments may be assembled from the side of the bed-plate, substantially as and for the purposes 10 described.

In testimony whereof, I affix my signature.

FRANK M. CLARK.
